UNITED STATES PATENT OFFICE.

GEORGE R. RICH, OF OAK PARK, ILLINOIS.

INTERNAL-COMBUSTION ENGINE.

1,076,911.

Specification of Letters Patent. Patented Oct. 28, 1913.

Application filed June 12, 1912. Serial No. 703,201.

To all whom it may concern:

Be it known that I, GEORGE R. RICH, a citizen of the United States, residing at Oak Park, in the county of Cook and State of Illinois, have invented new and useful Improvements in Internal-Combustion Engines, of which the following is a specification.

This invention relates to internal combustion engines and particularly to that type known as four cycle engines, although it is possible to apply the invention to two cycle engines.

The main object of this invention is to produce an easy running engine, of novel construction; to eliminate the use of puppet or other like valves and their accompanying valve gearing; and to minimize the noise, vibration and jarring to which the ordinary gas or gasoline engines are subject.

In the present embodiment of the invention I employ a rotatory port cover, as for instance a sleeve, for the inlet and exhaust ports of the cylinder, operatively driven from the piston, either directly or indirectly, and constructed and arranged in such manner as to open and close the ports at the proper intervals during the cycles of operation.

The invention consists in the several novel features hereinafter fully set forth in this specification and particularly defined in the claims.

The invention is clearly illustrated in the accompanying drawings in which:

Figure 1 is a vertical section of an upright engine embodying one form of the present invention, the section being taken on the broken line 1-1 in Fig. 2, Fig. 2 is a horizontal section thereof taken on the broken line 2-2 Fig. 1, Fig. 3 is a horizontal section taken on the line 3-3 Fig. 1, Fig. 4 is a detail, vertical section through the inlet port, showing the spark plug; Fig. 5 is a detail side elevation of a rotary sleeve or port cover, partly broken out to show the interior thereof, Fig. 6 is a diagrammatic view of a certain cam track which is associated with the sleeve, and which co-operates with means on the piston for effecting rotation of the sleeve in timed relation with the piston, Fig. 7 is a detail horizontal section of the piston, cylinder wall and sleeve taken on line 7-7 Fig. 1, Fig. 8 is a dia-

grammatic sectional view of one section of 55 said cam track, taken on line 8-8 Fig. 6, Fig. 9 is a perspective view of a fragment of the sleeve showing the construction at certain places on the track, Fig. 10 is a detail, vertical section through the piston, 60 cylinder wall and sleeve taken on line 10-10 Fig. 7, and illustrating a spring pressed pin that travels along the cam track and Fig. 11 is an end view of said pin and its support. 65

In the embodiment of the invention illustrated in said drawings 11, designates the outer shell or casing of the cylinder, 20, of an internal combustion engine, 12, the piston, and 13, the connecting rod which 70 connects the piston with a crank 14, carried by a crank shaft 15. In accordance with the common practice, a pin 16, secured to the piston and extending through one end of the connecting rod 13, connects the 75 piston with the connecting rod, and a wrist pin 17, of the crank 14, extends through a box 13^a, at the other end of the connecting rod and connects the latter with the crank. The usual bearings are provided for the 80 crank shaft and a crank case 18, is provided at the bottom of the engine for inclosing the shaft, crank and connecting rod. The crank case may comprise an upper section 18^a, and a lower section 18^b, bolted or otherwise secured together as shown, and said case is secured to the lower end of the shell 85 or casing 11, by bolts and nuts 19.

Within the outer shell or casing 11, is the cylindrical wall 20^a, of the cylinder 20, 90 which in the embodiment of the invention shown, is surrounded by a water jacket 21, extending part way down its side; its head 22, also is formed with a water jacket 21^a, opening to the water jacket around the 95 cylindrical wall 20^a. The cylinder 20, is bolted or otherwise secured to the shell or casing 11, by bolts 23, extending through flanges at the joint between the cylinder and casing. 100

A compression space 24, is provided at the top of the cylinder, and leading out from said compression space 24, are the inlet and exhaust passages 26 and 27; said passages may lead down between the outer face of the cylinder wall 20^a, and inner face of the water jacket 21, 21^a, to increase the 105 size of the compression space, and said pas-

sageways open out through the casing 11, by way of inlet and exhaust ports 28, 29. By way of preference, said ports are arranged in horizontal alinement with each other (when employed in an upright engine), and are spaced approximately 90 degrees apart; in such case the crank shaft 15, lies in a vertical plane extending midway between the ports, as shown in Fig. 2.

10 An annular space is left between the water jacket 21, and the casing 11, and in said space is a rotatory port cover or sleeve 30, whose cylindrical wall 31, surrounds that portion of the cylinder, containing the inlet and exhaust ports 28, 29, and in certain positions said sleeve closes both ports, whereas in a second position it opens the inlet port, keeping the exhaust port closed, and in a third position it closes the inlet port 20 and opens the exhaust port. In the form of port cover shown, a single opening 32, is provided in the wall 31, thereof, which opening is substantially of the same size and shape as the ports, and is arranged in horizontal alinement therewith, so that by turning the sleeve, the opening may be brought into register with either port.

25 The sleeve is shown as formed with a cylindrical wall 34, of slightly less diameter than the wall 31, and below said wall 34, it has an inwardly extending horizontal flange 35, below which is a cylindrical wall 36, which surrounds and fits upon the wall 20^a, of the cylinder 20. The flange portion 35, of the sleeve 30, rests upon a horizontal, circular supporting flange 37, that projects inward from the casing 11, and the bottom wall 21^a, of the water jacket 21, is arranged immediately above the flange 35, to prevent upward endwise movement of the sleeve.

30 The bearing surfaces on the sleeve and parts against which it bears, are machined to make perfect bearing surfaces, and if desired grooves may be formed in said bearing surfaces to reduce the size thereof, and also for the purpose of receiving lubricating oil. In fact the entire space between the cylinder shell and crank case may be filled 35 with lubricating oil, or the crank case may be filled with oil, and the parts may be lubricated by the oil splashed from the crank case. Operative means are provided for rotating said sleeve in time with the strokes of the piston, and by way of preference, said means are provided directly between the piston and sleeve, so as to dispense with the necessity of complicated gearing between the crank shaft and sleeve, although I realize that it is possible to use 40 gearing for driving the sleeve from the crank shaft.

In the form of the invention shown, a cam track 38, is provided upon the inner face of the wall 36, of the sleeve, said track 60 being here shown in the form of a continu-

ous, zigzag groove, a developed view of which is illustrated in Fig. 6. Secured to the piston 12, is a sleeve actuating device, here shown as comprising a pin or bolt 39, that projects out through a vertical slot 40, in the wall 20^a, of the cylinder and travels in said cam slot or track 38, and acts to rotate the sleeve part way around during each stroke of the piston. The invention being shown as applied to a four cycle engine, the cam slot contains four sections marked "intake," "compression," "explosion" and "exhaust" in Fig. 6; movement of the pin through any one section causes rotation of the sleeve through an arc of 90 degrees.

To insure a positive movement of the pin from one section of the cam slot to another, I provide co-acting means between the cam slot and pin, constructed and arranged to prevent the pin from traveling backward in the same section after it has once come into position at the meeting point of any two sections. In the form shown, the bottom surface 38^a, of each section of the track slopes from one end of the section to the other, as diagrammatically shown in Fig. 8, to form a shoulder or abutment 41, at the end of each section, against which abutment the pin strikes when the piston starts in a direction opposite to the one previously traveled by it. The pin 39, is spring pressed toward the bottom of the cam slot so that its end 39^a, continuously bears against the bottom of the slot, and when it reaches the end of a section it passes over the abutment and down into the bottom of the next section. In Fig. 10, is illustrated, in detail, one form of connecting means between the pin 39, and piston, said connecting means being here shown as comprising a sleeve 42, extending through the wall of the piston and secured thereto by means of a head 43, on one end and lock nut 44, upon its other end. In the inner end of the sleeve 42, is secured a block 45, and between said block and pin is a coiled compression spring 46, which acts to yieldingly press the pin outward and against the bottom of the cam slot.

Under certain conditions it is found that the sloping bottoms 38^a, and spring 46, for pressing the pin 39, against said bottoms may be dispensed with, because the momentum of the port cover or sleeve 30, acts to carry the latter onward, when the piston reaches the end of its stroke, but I have found that it is advantageous to bring the sleeve to a full stop at the end of each stroke of the piston, and in order to accomplish this result the high and low points of the cam slot are formed with vertical extensions 125 38^a, 38^b, (see Figs. 6 and 9) adapted to receive the pin 39, after it has moved through one section of the cam slot and before it begins its reverse movement in the other section, that is to say, at the ends of the strokes 130

of the piston the pin travels up and down through the vertical extensions 38^a, 38^b, of the cam slot, thereby permitting the sleeve to remain perfectly stationary for a certain length of time. In Fig. 6, the position assumed by the pin (when the piston and sleeve occupy the position illustrated in Fig. 1) is shown in solid lines, and the positions of the pin at the ends of the strokes, are shown in dotted lines.

In accordance with the common practice, a spark plug 50, is provided for igniting the charge and Fig. 4 shows said plug as secured in the wall of the cylinder adjacent to the inlet port.

In the operation of the engine, the charge is taken in on the intake stroke of the piston, at which time the opening 32, in the sleeve 30, registers with the intake port 28. The opening 32, is so located with respect to the cam slot 38, as to commence uncovering the inlet port 28, at or about the time that the piston begins its intake stroke. By the time the piston has reached the lower end of its intake stroke the pin 39, has traveled down the "intake" section of the cam slot and has moved the sleeve 30, through an arc of 90 degrees, thereby moving the opening 32, past the inlet port 28, and thereafter closing the same at the end of the intake stroke. During the compression stroke of the cylinder, the pin 39, moves along the "compression" section of the cam slot, thereby advancing the sleeve through an arc of 90 degrees. At the end of the compression stroke the charge is ignited and during the explosion stroke the pin moves along the "explosion" section of the cam slot and moves the sleeve through another arc of 90 degrees. During the compression and explosion strokes, the wall 31, of the sleeve covers both ports, and the opening 32, travels from the inlet to the exhaust port. At the beginning of the exhaust stroke of the piston, the opening 32, is in position about to register with the exhaust port 29, and as the piston travels through said exhaust stroke, the pin 39, travels up through the "exhaust" section of the cam slot, thereby moving the sleeve through an arc of 90 degrees and consequently moving the opening 32, past the exhaust port 29. Figs. 1 and 2 show the piston in a position assumed by it part way up on its exhaust stroke, the port 29, being shown as fully open, but as soon as the piston reaches the upper end of said exhaust stroke the sleeve will have been moved through an arc of 45 degrees from such position, thereby bringing said opening to a point between the inlet and exhaust ports and in position ready to uncover said inlet port upon the intake stroke of the piston.

I realize that various alterations and modifications of this device are possible without departing from the spirit of my in-

vention and I do not therefore desire to limit myself to the exact form of construction shown and described.

I claim as new and desire to secure by Letters Patent:

1. In an internal combustion engine, the combination of a cylinder, having an inlet port and an exhaust port, a reciprocating piston in said cylinder, a rotatory port cover movable across said ports, and having an opening capable of registering with said ports, and operative connections for rotating the port cover in timed relation with the piston, one element of which extends through a slot in the cylinder, and directly connects the piston with the port cover.

2. In an internal combustion engine, the combination of a cylinder having an inlet port and an exhaust port, a piston reciprocable in said cylinder, a rotatory sleeve movable across said ports and having an opening therethrough capable of registering with said ports, one at a time, and motion transmitting means on the piston and sleeve, including a pin extending through a slot in the cylinder, for transforming the rectilinear motion of the piston into the rotatory motion of the sleeve.

3. In an internal combustion engine, the combination of a cylinder, having an inlet port and an exhaust port, a piston reciprocable in said cylinder, a rotatory port cover movable across said ports and having an opening capable of registering with said ports, said port cover being provided with a zigzag cam track, the inclines of which are of spiral form, concentric with said piston, and a projection carried by said piston and projecting out through a vertical slot in the wall of the cylinder and operatively engaging said cam track to transmit motion from said reciprocable piston to said rotatory port covering.

4. In an internal combustion engine, the combination of a cylinder having an inlet port and an outlet port, a piston reciprocable in said cylinder, a rotary sleeve surrounding said cylinder and movable across said ports, and having an opening capable of registering with said ports, one at a time, said sleeve being formed with a continuous zigzag, grooved cam track, extending around its inner face, and a pin carried by said piston and traveling in said cam track and operating to rotate said sleeve in timed relation to the piston.

5. In an internal combustion engine, the combination of a cylinder, having an inlet port and an outlet port, a piston reciprocable in said cylinder, a rotatory sleeve movable across said ports and having an opening capable of registering with said ports, one at a time, said sleeve having a continuous undulated grooved track formed upon its inner face, and a pin carried by said pis-

- ton and moving therewith in a straight line, said pin extending out through a longitudinal slot in the wall of the cylinder and traveling in said track and operating to rotate 5 said sleeve in timed relation to the piston.
6. In an internal combustion engine, the combination of a cylinder having an inlet port and an outlet port, a piston reciprocable in said cylinder, a rotatory sleeve movable across said ports and having an opening 10 capable of registering with said ports, one at a time, said sleeve being provided with a continuous zigzag track, a projection carried by and moving with said piston, and 15 traveling along said track and operating to rotate said sleeve in one direction, and means for positively directing said pin from each section of the zigzag track to the next adjacent one, and thereby preventing retro- 20 grade motion of said sleeve.
7. In an internal combustion engine, the combination of a cylinder, having an inlet port and an outlet port, a piston reciprocable in said cylinder, a rotatory sleeve movable across said ports and having an opening 25 capable of registering with said ports, one at a time, said sleeve being provided with a continuous, zigzag, grooved track, the bottoms of which slope from one end to 30 the other in steplike arrangement to leave a shoulder at the end of each section, and a spring pressed pin carried by said piston and traveling in said track, said shoulders acting to direct said pin from the one track 35 section to the following one.
8. In an internal combustion engine, the combination of a water cooled cylinder, having an inlet port and an exhaust port, a piston reciprocable in said cylinder, a rotatory sleeve having a zigzag cam groove 40 on its inner face, said sleeve surrounding said cylinder and having a cylindrical wall traveling over said ports, said wall being formed with an opening capable of registering with said ports, and sleeve rotating 45 means including a pin carried by said piston, and extending out through a vertical slot in the cylinder wall, and traveling in the zigzag cam groove in said sleeve.
9. In an internal combustion engine, the combination of a water cooled cylinder, having an inlet port and an exhaust port, a piston reciprocable in said cylinder, an outer shell surrounding said cylinder and spaced 50 away therefrom to leave an annular space therebetween, said outer shell having ports registering with the ports of the cylinder, a rotatory sleeve having a cam groove therein and having a cylindrical wall rotatable in 55 said space between the cylinder and outer shell and said wall being formed with an opening capable of registering with said ports, and means carried by the piston and extending through a vertical slot in the cylinder wall and traveling in said cam groove.
10. In an internal combustion engine, the combination of a cylinder, having an inlet port and an exhaust port in its side wall, a piston in said cylinder, an outer shell surrounding said cylinder and forming its support, said outer shell having an inwardly projecting annular flange, a rotatory sleeve located between said outer shell and cylinder and having an opening capable of registering with said ports, said sleeve having a circular bearing face resting upon said annular flange, and a downward extension formed with a zig zag cam groove, and a pin carried by the piston, traveling in said cam groove, and operating to rotate said sleeve in timed relation to the piston.
11. In an internal combustion engine, the combination of a cylinder having an inlet port and exhaust port, a reciprocable piston in said cylinder, a rotatory sleeve surrounding said cylinder and having an opening capable of registering with said ports, a support for said sleeve, a continuous, zigzag cam track on the inner face of said sleeve, said cam track having extensions leading therefrom at their top and bottom points, a pin carried by the piston and traveling in said zigzag track and the extensions thereof, and means for directing said pin from each track extension to an adjacent section of the track.
12. In an internal combustion engine, the combination of a cylinder having an inlet port and an exhaust port, a reciprocable piston in said cylinder, a rotatory sleeve surrounding said cylinder and having an opening capable of registering with said ports, said sleeve being formed on its inner face with a continuous, zigzag, grooved cam track formed with grooved extensions at the top and bottom points of the track, a pin carried by the piston and traveling in said grooved cam track and its extensions, and means for directing said pin from any extension to the following section of the cam track.
13. In an internal combustion engine, the combination of a cylinder having an inlet port and an exhaust port, a reciprocable piston in said cylinder, a rotatory sleeve surrounding said cylinder and having an opening capable of registering with said ports, said sleeve being formed on its inner face with four right and left inclined connected grooves, arranged around the sleeve to form a continuous zigzag cam groove, the bottoms of the grooves sloping from end to end in steplike arrangement, and a spring pressed pin carried by the piston and traveling in said grooves.
14. In an internal combustion engine, the combination of a cylinder having an inlet port and an exhaust port, a reciprocable piston in said cylinder, a rotatory sleeve surrounding said cylinder and having an open-

ing capable of registering with said ports, said sleeve being formed on its inner face with four right and left inclined connected grooves arranged around the sleeve in the 5 form of a zigzag cam groove, the meeting points of said grooves having grooved extensions lying in the line of travel of the piston, a pin carried by the piston and traveling in said grooves and extensions, and

means for directing said pin from any extension to the following groove.

In witness whereof, I have hereunto signed my name at Chicago, Cook county, Illinois, this 10th day of June 1912.

GEORGE R. RICH.
